UNITED STATES PATENT OFFICE.

FREDERICK L. SAMPSON, OF ST. PAUL, MINNESOTA.

DESIGN FOR AN OVERCOAT.

SPECIFICATION forming part of Design No. 26,753, dated March 9, 1897.

Application filed October 29, 1894. Serial No. 527,348. Term of patent 7 years.

To all whom it may concern:

Be it known that I, FREDERICK L. SAMPSON, of St. Paul, Ramsey county, Minnesota, have invented and produced a new and useful Design for Overcoats, of which the following is a specification, reference being had to the accompanying drawings, forming part thereof, in which—

Figure 1 is a front view of an overcoat upon the wearer, illustrating my design; and Fig. 2 is a development of the upper part of the body of the coat and the collar outspread upon a plane surface.

In the drawings, A represents the body of the coat, and 2 the collar, integral therewith, said collar having substantially right-angled corners 3 extending, when upon the body of

the wearer, normally toward and arranged slightly forward of the points 4 of the shoulders of the wearer, the outline from the corners 3 forward and downward being a concave curve, while the outline of the rear edge of the collar from each corner is substantially a right line. 20

I claim—

The design for an overcoat, substantially as herein shown and described.

In testimony whereof I affix my signature in presence of two witnesses.

FREDERICK L. SAMPSON.

Witnesses:

J. G. BAILEY,
JOE HOWELL.
